UNITED STATES PATENT OFFICE.

RICHARD WHITAKER, OF NEW BRUNSWICK, NEW JERSEY, ASSIGNOR TO
THE NEVERSLIP MANUFACTURING COMPANY, OF SAME PLACE.

HORSESHOE-CALK.

SPECIFICATION forming part of Letters Patent No. 605,766, dated June 14, 1898.

Application filed February 26, 1898. Serial No. 671,750. (No model.)

To all whom it may concern:

Be it known that I, RICHARD WHITAKER, a citizen of the United States, residing at New Brunswick, in the county of Middlesex and State of New Jersey, have invented certain new and useful Improvements in Horseshoe-Calks, of which the following is a specification, reference being had therein to the accompanying drawings.

10 This invention relates to removable horseshoe-calks; and the improvement consists in the novel construction of the calk in connection with simple means for securing the same to horseshoes, whether said shoes are unattached or attached to a horse's hoof. Its objects are to obtain simple, durable, and inexpensive calks. I attain these objects by the construction illustrated in the accompanying drawings, in which—

20 Figure 1 represents, partly in side view and partly in section, a horseshoe showing in transverse section one heel-calk and a toe-calk constructed in accordance with my invention. Fig. 2 is a bottom view of a cylindrical shell-calk as shown on one heel of the shoe in Fig. 1, but without its fastening-screw. Fig. 3 is a bottom view of a hexagonal shell-calk. Fig. 4 is a perspective view of the screw-bolt for said hexagonal calk. 25 Fig. 5 is a bottom perspective view of a square shell-calk. Fig. 6 is a bottom perspective view of an octagonal shell-calk. Fig. 7 is a top perspective view of a cylindrical shell-calk as in Fig. 2, but provided with a short 30 polygonal boss or head.

35 In said drawings, A represents a horseshoe of any suitable and well-known form, to which is shown secured to one of the heels a cylindrical or tubular calk, preferably made of sheet-steel in the form of a shell B, having an inwardly-projecting collar b on its upper end. Said calk is secured to the shoe by means of a screw C, having a comparatively stout body and a thin head, having a slot 40 therein adapted to receive the end of a screw-driver or other suitable tool to rotate it.

45 In Fig. 3 is shown a hexagonal tubular shell-calk D. (Shown secured to the toe of the shoe in Fig. 1.) Said calk is also provided with an inwardly-projecting collar d on its upper end and is secured to the shoe by means of a bolt E, having a compara-

tively thin polygonal head e, made with the same number of faces as the calk and wholly surrounded by the walls of said calk.

55

The shell-calk F shown in Fig. 5 and the shell-calk G in Fig. 6 are modifications of the calk shown in Fig. 3 simply in the number of faces and are to be secured to the shoe with bolts having preferably polygonal heads with 60 corresponding number of faces.

The shell-calk B² shown in Fig. 7 is a modification of the cylindrical calk B. It is provided with a thin polygonal head b², intended to be received in a similar shallow polygonal depression in the shoe to prevent its rotation if a screw made with a cylindrical head is used as a fastener. The polygonal calks D F G may also with advantage be provided with a thin polygonal head, particularly if a screw 70 made with a cylindrical head is used to fasten them to a horseshoe. If a bolt having a polygonal head is used, its body is first passed through the calk and inserted into the screw-tapped hole a in the shoe and the bolt and 75 calk rotated together, first by the operator's hand and then with a wrench, until it obtains a firm hold against the bottom of the shoe.

As the calks are made with an endless periphery from top to bottom and a flat annular 80 bottom edge h there is no danger of a horse injuring itself with the calks while wearing them.

Having now fully described my invention, I claim—

85

1. A removable horseshoe-calk consisting of a polygonal tubular shell having an inwardly-projecting collar on its upper end, in combination with a polygonal-headed screw having the flat projecting part of its head adjacent to its body bearing against said collar and its faces in engagement with the polygonal inner sides of the calk, substantially as described.

2. A horseshoe-calk consisting of a tubular shell having an inwardly-projecting collar on its upper end and a hollow polygonal head on top of said collar, substantially as described.

In testimony whereof I affix my signature in presence of two witnesses.

RICHARD WHITAKER.
